UNITED STATES PATENT OFFICE.

GEORGE H. BLACK, OF ROCHESTER, NEW YORK, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENING-INSERTING MACHINE.

1,301,032.

Specification of Letters Patent. Patented Apr. 15, 1919.

Application filed November 10, 1917. Serial No. 201,371.

To all whom it may concern:

Be it known that I, GEORGE H. BLACK, a citizen of the United States, residing at Rochester, in the county of Monroe and 5 State of New York, have invented certain Improvements in Fastening-Inserting Machines, of which the following description, in connection with the accompanying drawings, is a specification, like reference characters on the drawings indicating like parts in the several figures.

This invention relates to fastening inserting machines and particularly to machines organized for use in shaping the work 15 and preferably then applying a fastening to secure the work in its shaped condition. The invention has been applied with commercially advantageous results to the production of shoe insoles and particularly to 20 the production of an insole which constitutes the subject-matter of a co-pending application Ser. No. 201,372 filed by me on even date herewith.

A feature of the invention consists in the 25 combination of fastener inserting mechanism with work supporting means and work shaping means arranged to force a portion of the work into a predetermined relation to the body of the work and hold it in operative relation to the fastener inserting mechanism. This feature of the invention is herein shown as embodied in a work supporting table comprising a clenching surface over which an insole may be moved in the 30 act of presenting the insole to the fastening mechanism, combined with a shaping member constructed and arranged with relation to the table and inserting mechanism to engage the upstanding lip or sewing rib of an insole during the movement of the insole into position to be operated upon and by such arrangement to bend the insole lip inwardly away from the edge of the insole and hold it in such bent position, while the 35 fastener inserting mechanism drives a fastener in position to secure the lip in its bent over position against the outwardly directed strain of the inseam which is to connect the shoe upper to the insole. Other features of 40 the invention including certain details of construction and combinations of parts will appear from the following description of an illustrated embodiment of the invention and will then be pointed out in the claims.

Figure 1 of the accompanying drawings is 55 a perspective view of a machine embodying this invention.

Fig. 2 is an enlarged view of the work table and work shaping means.

Fig. 3 is a transverse sectional view 60 through an insole and the machine work table illustrating the operation of the machine.

The tack driving mechanism herein shown for illustrative purposes and which has been 65 demonstrated to be commercially advantageous to use is of the type known in the trade as the Boston tacker, an example of which is illustrated and described in United States Letters Patent No. 389,275, Woodward. This mechanism comprises tack supplying means and tack driving means including a movably supported nozzle 2 and a connection between said nozzle and a tripping mechanism so arranged and organized 70 that upward movement of the nozzle by the work will operate the tripping mechanism 75 to cause the power to be applied for inserting a previously separated fastening and for separating another fastening and then come 80 automatically to rest. This machine as herein illustrated is also provided with a vertically movable work table operated by a treadle 5 to move the work into contact with the nozzle and then lift the nozzle to cause 85 the tripping action above described.

As herein illustrated the work table 10 is constructed and arranged with the top surface suitable for supporting a welt shoe insole and allowing the insole to be presented 90 by a sliding movement backwardly over the table. Associated with the table and overlying the rear portion thereof is a forwardly projecting spring plate 12 spaced above the surface of the table sufficiently to enable the 95 feather portion of the insole to be thrust under the plate. The front edge of the plate is shaped and arranged to engage the usual upstanding sewing rib of the insole and to crowd and bend said rib inwardly away 100 from the edge of the insole. Said plate also preferably has an opening 13 located under the nozzle 2, the plate thereby presenting a construction initially engaging the sewing rib throughout the width of the plate and during the tacking operation engaging the 105 rib on either side of the tack nozzle to hold the lip in inwardly bent position adjacent

to the tacking point. The spring plate is spaced above the work table by a block 14 which also preferably constitutes an edge gage to limit the insertion of the insole 5 under the nozzle to such a position that the tack will be driven through the inwardly bent rib and into the body of the insole in suitable or desired relation to the root or base of the rib to adapt said tack to hold 10 the rib in its inwardly bent position during the sewing of the inseam and to assist in maintaining said rib in such a position against the outward strain of the shoe upper after the inseam has been sewed. The 15 plate 12 and block 14 are held in place on the table 10 by a bolt 15, the bolt holes in the plate and block being elongated to allow said parts to be adjusted relatively to each other and to the tack nozzle 2. Preferably 20 the spring plate will be constructed and arranged to force the rib inwardly on that side of the tacking point which is the more remote from the heel end of the insole and to assist the operative in positioning the insole longitudinally so that the tack will be 25 inserted immediately back of the point where the last inseam should be taken, or at the extreme rear end of the inseam. The object of this arrangement is to obtain the 30 maximum efficiency of the apparatus in shaping the rib in the rear part of the shank and of the fastening tack in holding the rib in its inwardly bent position and yet have the tack where it shall not be an obstruction 35 to the needle in inserting the end stitch of the inseam. The tack thus properly located is used by the inseam sewing machine operative to determine the point at which the inseam shall be begun or terminated. It 40 is desirable to bend inwardly and fasten the insole rib at both the inner and outer sides of the shank of the insole and in practice an operative presents the insole and shapes and fastens the rib on the one side 45 and then takes out the insole and turns it around and shapes and fastens the rib at the other side. In this use of the machine the heel end of the insole is pointing to the right in one case and to the left in the 50 other case. The rib bending and work gaging device is therefore symmetrically formed with relation to the nozzle opening to contribute to the production of uniform 55 results at the two sides of the insole. It is obvious that the instrumentality which gages the position of the insole to locate the tack at the right distance inwardly from the edge of the insole may be integral with or 60 separate from the rib bending means and may be adjustable with relation thereto to provide as above described or otherwise, for example, for working upon insoles having different widths of feathers, and that the instrumentality by the aid of which the 65 work is positioned longitudinally of the in-

sole may be integral with or independent of the rib bending means. The rib bending means is herein shown as a spring plate and has been referred to in this description for identification purposes as a spring plate but 70 it is obvious that no limitation in this respect is intended by the use of this expression.

The fastening employed for securing the lip in its bent down position is shown as a 75 short slender tack which is inserted through the lip and into the body of the insole and preferably is clenched on the lower face of the insole, but other suitable fastening means may be employed. In the use of the 80 machine the sewing rib of the insole is bent inwardly and is subsequently compressed in its inwardly bent position between the work table and the nozzle and thereafter the tack driver applies a blow to the inwardly bent 85 rib. It is within this invention to employ less than all of the rib shaping instrumentalities, as for example, to employ the rib bending means with or without means to effect the compression of the inwardly bent 90 rib or with or without means to deliver a blow or to fasten the inwardly bent rib.

Having explained the nature of this invention and described an illustrative embodiment thereof, I claim as new and desire 95 to secure by Letters Patent of the United States:—

1. In a machine of the class described, the combination of a work supporting table and a rib bending device relatively arranged to 100 permit an insole to be thrust sidewise across the table and under the bending device for bending the rib inwardly from the edge of the insole, and means for fastening the rib in its inwardly bent position.

2. In a machine of the class described, the combination of a work supporting table and a rib bending device relatively arranged to 110 permit an insole to be thrust sidewise across the table and under the bending device for bending the rib inwardly from the edge of the insole, and a fastening inserting mechanism between which and said work supporting and shaping means there is provision for relative movement in a predetermined path for causing a fastening to be inserted in position to hold the rib in its inwardly bent position.

3. In a machine of the class described, the combination of a work supporting table and a rib bending device relatively arranged to 120 permit an insole to be thrust sidewise across the table and under the bending device for bending the rib inwardly from the edge of the insole, tack inserting mechanism located 125 above the work table, and means for moving the work table to press the inwardly bent portion of the rib against the fastening mechanism and hold it under pressure while the fastening is inserted.

4. In a machine of the class described, the combination of a work supporting table and a rib bending device relatively arranged to permit an insole to be thrust sidewise across the table and under the bending device for bending the rib inwardly from the edge of the insole, said device being constructed and arranged to hold the rib in inwardly bent position while a fastening is applied to 10 cure the rib in that position.
5. In a machine of the class described, the combination of a fastening inserting mechanism, a work supporting table and a rib bending device relatively arranged to permit an insole having a sewing rib to be thrust under the bending device for bending the rib inwardly from the edge of the insole, said bending device being constructed and arranged to expose a portion of the rib 15 between two inwardly bent portions whereby the exposed portion may be subjected to the operation of the fastening inserting mechanism.
6. In a machine of the class described, the combination with a work table adapted to receive an insole having a sewing rib, of means to bend the sewing rib inwardly from the edge of the insole, fastener inserting mechanism, and means to position the insole 20 laterally with relation to the fastener inserting mechanism to present the rib in the plane of action of said mechanism.
7. In a machine of the class described, the combination of a work table adapted to receive a sewing rib, means for bending the sewing rib inwardly, means for gaging the lateral position of the insole, means to assist the operator in gaging the longitudinal position of the insole, and means operating 25 in predetermined relation to said gaging means to insert a fastening for securing the rib in inwardly bent position at a point determined by said gaging means.
8. In a machine of the class described, means adapted for use in bending the rear end portion of a welt insole sewing rib inwardly from the edge of the insole, and means for fastening the rib.
9. A machine of the class described comprising, in combination, a fastening inserting mechanism, and insole supporting means constructed and arranged to cause the sewing rib of a welt insole to be bent inwardly from the edge of the insole and presented 30 in said bent position for the operation of the fastening inserting mechanism.
10. In a machine of the class described, the combination of a fastening inserting mechanism, and a work supporting table having a clenching surface and an insole rib 60 shaping member constructed and arranged with relation to the table and the inserting mechanism to engage the upstanding sewing rib of the insole during the movement of the sole into position to be operated upon and 65 bend the insole lip inwardly away from the edge of the insole and into position to be operated upon by the fastening inserting mechanism.
11. In a machine of the class described, the combination of means for supporting a welt insole having a sewing rib, relatively arranged means adapted to engage the sewing rib and bend it inwardly away from the edge of the insole, and fastening inserting 70 means operating to fasten the sewing rib in its inwardly bent position.
12. In a machine of the class described, the combination of fastening inserting mechanism, an insole support movable between 80 inoperative and operative insole clamping relation to the fastening inserting mechanism, and means constructed and arranged with relation to the insole support and the fastening inserting mechanism to engage the 85 sewing rib of an insole and bend it inwardly away from the edge of the insole and into the plane of action of the fastening inserting mechanism during the movement of the insole into operative relation to 90 the fastening inserting mechanism.
13. In a machine of the class described, the combination of a fastening inserting mechanism, a relatively movable insole support constructed and arranged to present an 95 insole having a sewing rib to the fastening inserting mechanism, and sewing rib engaging means operating to force the outer wall of the sewing rib into the plane of operation of the inserting mechanism.
14. A machine of the class described having, in combination, means to support a welt insole sewing rib, rib shaping means including means to crowd the rear end portion of the sewing rib inwardly from the edge of the insole and bend it over upon the body of the insole, and means for fastening the rib in its 105 inwardly crowded and bent-over relation to the body of the insole.

In testimony whereof I have signed my 110 name to this specification.

GEORGE H. BLACK.
